APPARATUS FOR WRAPPING OF BLOCK-SHAPED ARTICLES

Joseph Arthur Gilbert, Gainsborough, England,
assignor to Rose Brothers (Gainsborough)
Limited, Gainsborough, England, a British
company

Application February 21, 1945, Serial No. 579,007
In Great Britain February 26, 1944

14 Claims. (Cl. 93—7)

1

This invention relates to the wrapping of block-shaped articles, i. e., articles having a rectangular cross-section. Examples of such articles are blocks of chocolate, packets of cigarettes, blocks of ice cream that have been treated to render them sufficiently hard for wrapping purposes and other articles of similar shape.

The invention is concerned with a new or improved method of wrapping and with apparatus for carrying out such method.

According to the invention there is provided a method of wrapping block-shaped articles, comprising continuously feeding a spaced succession of articles in timed relation to the feeding of a succession of wrappers in a direction transverse to that of movement of the articles so that the forward end of each article in turn engages a wrapper and by further forward movement in co-operation with folding elements causes the wrapper to fold about the forward end and the upper and lower sides of the article, and transferring the partially wrapped articles in turn to separate pockets in a folding member arranged for movement in a direction transverse to that of movement of the articles on the conveyor, said folding member co-operating with further folding elements to complete the folding of the wrappers about each article in the form of a tube and then to fold extending portions of the wall of the tube on to the ends of the article to complete the wrapping of the article.

The invention also includes apparatus for wrapping block-shaped articles, comprising an endless conveyor provided with spaced feeding elements adapted to forward the articles in continuous succession towards the wrapping elements, means for feeding a succession of wrappers, in timed relation to the movement of the feeding elements, in a direction transverse to the direction of movement of the articles in such a manner that each article in turn engages a wrapper, means co-operating with the advancing article for folding the wrapper about the forward end and the upper and lower sides of the article, a folding member arranged for movement in timed relation to the conveyor in a transverse direction with respect to the conveyor, said folding member being provided with a series of pockets each adapted in turn to receive an article from the conveyor, and means co-operating with

2

said folding member for completing the folding of the wrapper about each article in the form of a tube and then folding extending wall portions of the tube on to the ends of the article to complete the wrapping of the article.

The endless conveyor may be in the form of a pair of endless chains connected at spaced intervals by pusher bars, the pusher bars being provided with pushers which extend through a slot in an article-supporting platform and are arranged to engage the rear faces of the articles for the purpose of feeding them along the supporting platform.

The folding member is conveniently in the form of a rotatable pocket wheel having a series of pockets each adapted to receive a partially wrapped article from the conveyor, the pockets conveniently having one yieldable side for facilitating the entry and exit of the articles and the folding operations.

The invention will now be described in greater detail with reference to the accompanying diagrammatic drawings, in which—

Figure 1 is an elevation, partly in section, showing the salient features of a machine for wrapping blocks of ice cream.

Figure 2 is a plan view of the apparatus shown in Figure 1.

Figure 3 is an elevation of a portion of the apparatus shown in Figure 1, drawn to a larger scale than Figures 1 and 2, and

Figures 4, 5, 6 and 7 illustrate different stages in the wrapping operation.

Referring to Figures 1 and 2, a succession of articles 11 (in this case blocks of ice cream that have been treated to render them sufficiently hard for wrapping purposes) are delivered to the machine by a belt conveyor 12, the articles being arrested by a stop 13 operating in timed relation to the machine so as to allow each article to move forward as it is required by the machine. As the stop 13 is raised, the leading article 11 is gripped by a pair of belts 14 and delivered to a supporting platform 16, the belts 14 being arranged to travel at a faster rate than the belt 12 so as to separate the leading article from the next succeeding one and allow the stop member 13 to be once more lowered into the path of the articles. As the article 11 is delivered by the belts 14 to the platform 16, a reciprocating drag member 17 is caused

to move into engagement with the rear face of the article and drag it forward along the supporting platform 16 into the path of a feed conveyor consisting of a pair of chains 18 connected at spaced intervals by pusher bars 19 each provided with a pusher 21 extending through a slot 22 in the supporting platform 16 and arranged to engage the rear face of the article as it is delivered by the drag member 17. The articles 11 are thus fed along the supporting platform 16, between a pair of side guides 23, at spaced intervals.

Arranged above the conveyor is a pair of wrapper feed rollers 24 which withdraw a web 26 of wrapping material from a roll 27 rotatably mounted at 28 and feed it to a wrapper guide 29 which leads the web across the path of the articles 11, a slot 31 being provided in the platform 16 for this purpose. As the leading article reaches the web 26 extending from the guide 29, a length of wrapper is severed from the web 26 by a pair of cutters 32 and is caused to fold round the forward end and the upper and lower surfaces of the article 11 by its advancing movement in co-operation with upper and lower guides 33. The pushers 21 and the wrapping material are arranged to travel continuously so that there is no delay in the feeding of the wrapper for the next succeeding article, the leading article with its wrapper and the pusher moving clear of the wrapper guide 29 in sufficient time to allow the web 26 of wrapping material to be fed again across the path of the articles before the next succeeding article reaches the wrapper. The timing of the conveyor and the wrapper feed is such that when the wrapper has been folded round the article as it is pushed into the guides 33 by the pusher, the wrapping material extends on the lower face of the article substantially to the rear edge of the article while from the upper surface of the article it extends rearwardly by an amount sufficient to complete the wrapping of the article. It will be understood that the web 26 is of sufficient width to extend beyond the ends of the article by amounts sufficient to form end folds.

As the leading article with its wrapper is pushed into the guides 33 by the pusher 21, it is transferred from there to a pocket 34 of a pocket wheel 36 by a pair of transfer members 37 arranged one on each side of the conveyor and arranged to move synchronously into engagement with the rear face of the article and by an accelerating motion move the article clear of its pusher 21 and then by a decelerating motion discharge the article gently into the pocket 34. The transfer members 37 are each provided with a positioning flange 38 arranged to engage the adjacent end face of the article so as to centralise the article during its transfer to the pocket 34. The transfer members 37 are operated in a known manner by a pair of parallel motion linkages 39 and 41 under the influence of an eccentric 42 and a cam 43.

The pocket wheel 36 is mounted on a shaft 44 and arranged to be driven intermittently in timed relation to the movement of the pushers 21 by a Geneva mechanism 45, of known construction, arranged to move the pockets 34 in turn to a series of stations. The pockets 34 have their trailing sides 46 formed on arms 47 pivoted at 48 and provided with cam rollers 49 arranged to engage a stationary cam 51. Springs 52 are provided for urging the arms into closed position. The trailing sides 46 of the pockets 34 are thus

yieldable and are positively opened by the cam 51 at certain stations as will appear from later description.

After the article has been transferred to the pocket 34 with its wrapper extending rearwardly from the upper surface of the article as explained above, the pocket wheel 36 is rotated through one eighth of a revolution to bring a further pocket to the article-receiving station where a further article is transferred to the pocket wheel as explained above. During such motion of the pocket wheel 36, the trailing edge of the pocket (which was opened by the cam 51 as the pocket approached the article-receiving station for the purpose of facilitating the entry of the article) is closed and the extending length of the wrapper is folded over the rear face of the article by engagement with a stationary folding member 53. The pocket wheel is then turned through a further eighth of a revolution to bring the pocket 34 containing the leading article to a first folding station, during which movement the trailing side 46 is once more opened to facilitate the folding operation. At this stage, the portion of the wrapper still extending from the rear face of the article is folded around the article into overlapping relationship with the opposing edge of the wrapper by a tucker blade 54 mounted on an arm 56 pivoted at 57 and arranged to be oscillated by suitable mechanism in timed relation to the movement of the pocket wheel. The article is thus surrounded by the wrapper in the form of a tube having portions extending from each end of the article. The pocket wheel 36 is then rotated through a further eighth of a revolution to carry the partially wrapped article to an end-folding station, and during such motion the trailing side of the pocket 34 is once more closed.

At the end-folding station, a pair of rotary folders 58 first engage the portions of the wrapper extending from the ends of the article in such a manner as to press one side thereof towards its opposing side so as partially to form pairs of side flaps as illustrated in Figures 4 and 5. As the rotary folders 58 are about to pass out of contact with the wrapper, a pair of first rotary side folders 59 move into contact with the partially formed side flaps on that side of the article and press them against the end of the article to complete their formation. The side folders 59 are articulated at 61 and each provided with a cam roller 62 arranged to engage a stationary cam 63 which causes the tips of the folders to follow a path appropriate to the natural lines of folding of the side flaps (see Figures 3 and 6). As the side folders 59 are about to complete their folding movements a pair of second side folders 64 move into contact with the remaining partially formed side flaps and press them against the already folded side flaps, so that each pair of side flaps together constitute an end flap having a triangular portion extending from the article in a transverse direction as shown in Figure 7.

For clarity of illustration, the supporting bearings for the folders at the end-folding station, as well as the driving mechanism therefor have not been completely shown. It will be understood, however, that the various folders are driven in timed relationship to each other and to the movement of the pocket wheel 36.

After the formation of the end flaps as described above, the pocket wheel 36 makes a further eighth of a revolution to carry the wrapped

article to a delivery station and during this movement the trailing side of the pocket is once more opened to facilitate ejection of the article. At the delivery station a pair of ejecting pushers 66 carried on a pair of continuously moving chains 67 operating in timed relationship to the movement of the pocket wheel 36 are moved into position behind the article and eject it into a delivery channel 68. The base of the delivery channel 68 is formed with a pair of curved slots 69 into which the triangular portions of the end flaps pass during the ejection of the wrapped article from the pocket wheel, and during further movement of the wrapped article along the channel 68 the curved slots 69 fold the triangular portions of the end flaps underneath the article to complete the wrapping. From the delivery channel the wrapped articles are conveyed by the pushers 66 to a collection station.

I claim:

1. Apparatus for wrapping block-shaped articles, comprising an endless conveyor provided with spaced feeding elements adapted to forward the articles in continuous succession towards the wrapping elements, means for feeding a succession of wrappers in timed relation to the movement of the feeding elements in a direction transverse to the direction of movement of the articles in such a manner that each article in turn engages a wrapper, means co-operating with the advancing movement of the article for folding the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted in turn to receive an article from the conveyor, a pair of transfer members arranged one on each side of the conveyor and adapted during their transferring motion to move, in a path parallel to that of the articles, synchronously into engagement with the rear face of each article in turn and by an accelerating motion move the article clear of its pusher and then by a decelerating motion discharge the article gently into a pocket of the pocket wheel, a pair of positioning flanges formed one on each transfer member and each arranged to engage an end face of the article so as to guide it in a lateral direction, and means co-operating with said pocket wheel for completing the folding of the wrapper about each article in the form of a tube and then folding extending wall portions of the tube on to the ends of the articles to complete the wrapping of the article.

2. Apparatus for wrapping block-shaped articles, comprising a conveyor consisting of a pair of endless chains connected at spaced intervals by pusher bars provided with pushers arranged to protrude through a longitudinal slot in an article-supporting platform extending between said chains, means for continuously driving said conveyor towards the wrapping elements, means for feeding a succession of articles on to said platform in timed relationship with the movement of the pushers so that a continuous succession of articles are fed towards the wrapping elements, means for feeding a succession of wrappers in timed relationship with the movement of the pushers in a direction transverse to that of movement thereof in such a manner that each article in turn engages a wrapper, means co-operating with the advancing article for folding

the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted in turn to receive an article from the conveyor, a pair of transfer members arranged one on each side of the conveyor and adapted during their transferring motion to move, in a path parallel to that of the articles, synchronously into engagement with the rear face of each article in turn and by an accelerating motion move the article clear of its pusher and then by a decelerating motion discharge the article gently into a pocket of the pocket wheel, a pair of positioning flanges formed one on each transfer member and each arranged to engage an end face of the article so as to guide it in a lateral direction, and means co-operating with said pocket wheel for completing the folding of the wrapper about each article in the form of a tube and then folding extending wall portions of the tube on to the ends of the articles to complete the wrapping of the article.

3. Apparatus according to claim 1, wherein the pockets of the pocket wheel each have one yieldable side for facilitating the entry and exit of the articles and the folding operations.

4. Apparatus according to claim 2, wherein the pockets of the pocket wheel each have one yieldable side for facilitating the entry and exit of the articles and the folding operations.

5. Apparatus according to claim 1, wherein the means cooperating with the pocket wheel comprises rotary end folders adapted to engage the portions of the wrapper extending from the ends of the article in the form of a tube in such a manner as to press one side thereof towards its opposing side so as partially to form pairs of side flaps extending from the ends of the article, and rotary side folders adapted to complete the formation of the side flaps by folding them successively against the ends of the article in such a manner that each pair of side flaps together constitute an end flap having a triangular portion extending from the article in a transverse direction.

6. Apparatus according to claim 2, wherein the pocket wheel comprises rotary end folders adapted to engage the portions of the wrapper extending from the ends of the article in the form of a tube in such a manner as to press one side thereof towards the opposing side so as partially to form pairs of side flaps extending from the ends of the article, and rotary side folders adapted to complete the formation of the side flaps by folding them successively against the ends of the article in such a manner that each pair of side flaps together constitute an end flap having a triangular portion extending from the article in a transverse direction.

7. Apparatus for wrapping block-shaped articles, comprising an endless conveyor provided with spaced feeding elements adapted to forward the articles in continuous succession towards the wrapping elements, means for feeding a succession of wrappers in timed relation to the movement of the feeding elements in a direction transverse to the direction of movement of the articles in such a manner that each article in turn engages a wrapper, means co-operating with the advancing article for folding the wrapper about the forward end and the upper and lower sides of the article, a pocket wheel arranged for inter-

mittent rotation about an axis transverse to that of movement of the articles in timed relationship with the movement thereof, said pocket wheel being provided with a series of pockets each adapted in turn to receive an article from the conveyor, rotary end folders in association with said pocket wheel and arranged to engage the portions of the wrapper extending from the ends of the article in the form of a tube in such a manner as to press one side thereof towards its opposing side so as partially to form pairs of side flaps extending from the ends of the articles, pairs of rotary side folders in association with said pocket wheel and arranged to complete the formation of the side flaps by folding them successively against the ends of the article in such a manner that each pair of side flaps together constitute an end flap having a triangular portion extending from the article in a transverse direction, the first folder of each pair of side folders being articulated, and cam means for causing the tips of said first folders to follow a path appropriate to the natural lines of folding of the side flaps.

8. Apparatus for wrapping block-shaped articles, comprising a conveyor consisting of a pair of endless chains connected at spaced intervals by pusher bars provided with pushers arranged to protrude through a longitudinal slot in an article-supporting platform extending between said chains, means for continuously driving said conveyor towards the wrapping elements, means for feeding a succession of articles on to said platform in timed relationship with the movement of the pushers so that a continuous succession of articles are fed towards the wrapping elements, means for feeding a succession of wrappers in timed relationship with the movement of the pushers in a direction transverse to that of movement thereof in such a manner that each article in turn engages a wrapper, means co-operating with the advancing movement of the article for folding the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted in turn to receive an article from the conveyor, rotary end folders in association with said pocket wheel and arranged to engage the portions of the wrapper extending from the ends of the article in the form of a tube in such a manner as to press one side thereof towards its opposing side so as partially to form pairs of side flaps extending from the ends of the article, pairs of rotary side folders in association with said pocket wheel and arranged to complete the formation of the side flaps by folding them successively against the ends of the article in such a manner that each pair of side flaps together constitute an end flap having a triangular portion extending from the article in a transverse direction, the first folder of each pair of side folders being articulated, and cam means for causing the tips of said first folders to follow a path appropriate to the natural lines of folding of the side flaps.

9. Apparatus for wrapping block-shaped articles comprising an endless conveyor provided with spaced feeding elements adapted to forward the articles in continuous succession towards the wrapping elements, means for feeding a succession of wrappers in timed relation to the movement of the feeding elements in a direction trans-

verse to the direction of movement of the articles in such a manner that each article in turn engages a wrapper, means co-operating with the advancing movement of the articles for folding the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted in turn to receive an article from the conveyor, a pair of transfer members arranged one on each side of the conveyor and adapted during their transferring motion to move, in a path parallel to that of the articles, synchronously into engagement with the rear face of each article in turn and by an accelerating motion move the article clear of its pusher and then by a decelerating motion discharge the article gently into a pocket of the pocket wheel, a pair of positioning flanges formed one on each transfer member and each arranged to engage an end face of the article so as to guide it in a lateral direction, rotary end folders in association with said pocket wheel and arranged to engage the portions of the wrapper extending from the ends of the article in the form of a tube in such a manner as to press one side thereof towards its opposing side so as partially to form pairs of side flaps extending from the ends of the article, pairs of rotary side folders in association with said pocket wheel and arranged to complete the formation of the side flaps by folding them successively against the ends of the article in such a manner that each pair of side flaps together constitute an end flap having a triangular portion extending from the article in a transverse direction, the first folder of each pair of side folders being articulated and cam means for causing the tips of said first folders to follow a path appropriate to the natural lines of folding of the side flaps.

10. Apparatus for wrapping block-shaped articles, comprising a conveyor consisting of a pair of endless chains connected at spaced intervals by pusher bars provided with pushers arranged to protrude through a longitudinal slot in an article-supporting platform extending between said chains, means for feeding a succession of articles on to said platform in timed relationship with the movement of the pushers so that a continuous succession of articles are fed towards the wrapping elements, means for feeding a succession of wrappers in timed relationship with the movement of the pushers in a direction transverse to that of movement thereof in such a manner that each article in turn engages a wrapper, means co-operating with the advancing article for folding the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted in turn to receive an article from the conveyor, a pair of transfer members arranged one on each side of the conveyor and adapted during their transferring motion to move, in a path parallel to that of the articles, synchronously into engagement with the rear face of each article in turn and by an accelerating motion move the article clear of its pusher and then by a decelerating motion discharge the article gently into a pocket of the pocket wheel, a pair of positioning flanges formed one on each transfer

member and each arranged to engage an end face of the article so as to guide it in a lateral direction, rotary end folders in association with said pocket wheel and arranged to engage the portions of the wrapper extending from the ends of the article in the form of a tube in such a manner as to press one side thereof towards its opposing side so as partially to form pairs of side flaps extending from the ends of the article, pairs of rotary side folders in association with said pocket wheel and arranged to complete the formation of the side flaps by folding them successively against the ends of the article in such a manner that each pair of side flaps together constitute an end flap having a triangular portion extending from the article in a transverse direction, the first folder of each pair of side folders being articulated, and cam means for causing the tips of said first folders to follow a path appropriate to the natural lines of folding of the side flaps.

11. Apparatus for wrapping block-shaped articles, comprising an endless conveyor provided with spaced feeding elements adapted to forward the articles in continuous succession towards the wrapping elements, means for feeding a succession of wrappers in timed relation to the movement of the feeding elements in a direction transverse to the direction of movement of the articles in such a manner that each article in turn engages a wrapper, means co-operating with the advancing movement of the article for folding the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted in turn to receive an article from the conveyor, a pair of transfer members arranged one on each side of the conveyor and adapted to move synchronously into engagement with the rear face of each article in turn and by an accelerating motion move the article clear of its pusher and then by a decelerating motion discharge the article gently into the pocket of the pocket wheel, and means co-operating with said pocket wheel for completing the folding of the wrapper about each article in the form of a tube and then folding extending wall portions of the tube on to the ends of the article to complete the wrapping of the article.

12. Apparatus for wrapping block-shaped articles, comprising a conveyor consisting of a pair of endless chains connected at spaced intervals by pusher bars provided with pushers arranged to protrude through a longitudinal slot in an article-supporting platform extending between said chains, means for continuously driving said conveyor towards the wrapping elements, means for feeding a succession of articles on to said platform in timed relationship with the movement of the pushers so that a continuous succession of articles are fed towards the wrapping elements, means for feeding a succession of wrappers in timed relationship with the movement of the pushers in a direction transverse to that of movement thereof in such a manner that each article in turn engages a wrapper, means co-operating with the advancing article for folding the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted

in turn to receive an article from the conveyor, a pair of transfer members arranged one on each side of the conveyor and adapted to move synchronously into engagement with the rear face of each article in turn and by an accelerating motion move the article clear of its pusher and then by a decelerating motion discharge the article gently into the pocket of the pocket wheel, and means co-operating with said pocket wheel for completing the folding of the wrapper about each article in the form of a tube and then folding extending wall portions of the tube on to the ends of the article to complete the wrapping of the article.

13. Apparatus for wrapping block-shaped articles, comprising an endless conveyor provided with spaced feeding elements adapted to forward the articles in continuous succession towards the wrapping elements, means for feeding a succession of wrappers in timed relation to the movement of the feeding elements in a direction transverse to the direction of movement of the article in such a manner that each article in turn engages a wrapper, means co-operating with the advancing movement of the article for folding the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted in turn to receive an article from the conveyor, rotary end folders in association with said pocket wheel and adapted to engage the portions of the wrapper extending from the ends of the article in such a manner as to press one side thereof towards its opposing side so as partially to form pairs of side flaps extending from the ends of the article, and rotary side folders adapted to complete the formation of the side flaps by folding them successively against the ends of the article in such a manner that each pair of side flaps together constitute an end flap having a triangular portion extending from the article in a transverse direction.

14. Apparatus for wrapping block-shaped articles, comprising a conveyor consisting of a pair of endless chains connected at spaced intervals by pusher bars provided with pushers arranged to protrude through a longitudinal slot in an article-supporting platform extending between said chains, means for continuously driving said conveyor towards the wrapping elements, means for feeding a succession of articles on to said platform in timed relationship with the movement of the pushers so that a continuous succession of articles are fed towards the wrapping elements, means for feeding a succession of wrappers in timed relationship with the movement of the pushers in a direction transverse to that of movement thereof in such a manner that each article in turn engages a wrapper, means co-operating with the advancing article for folding the wrapper about the forward end and the upper and lower sides of the article, a pocket wheel arranged for intermittent rotation about an axis transverse to that of movement of the conveyor in timed relationship with the movement thereof, said pocket wheel being provided with a series of pockets each adapted in turn to receive an article from the conveyor, rotary end folders in association with said pocket wheel and adapted to engage the portions of the wrapper extending from the ends of the article in the form of a tube in such a manner as to press

11

one side thereof towards its opposing side so as partially to form pairs of side flaps extending from the ends of the article, and rotary side fold-
ers adapted to complete the formation of the side flaps by folding them successively against the ends of the article in such a manner that each pair of side flaps together constitute an end flap having a triangular portion extending from the article in a transverse direction.
